INVENTOR

John Bullard Brooks
By Cornell, Atty.

UNITED STATES PATENT OFFICE.

JOHN BOULTBEE BROOKS, OF BIRMINGHAM, ENGLAND.

CYCLE-SADDLE.

SPECIFICATION forming part of Letters Patent No. 484,289, dated October 11, 1892.

Application filed April 8, 1892. Serial No. 428,366. (No model.) Patented in England September 30, 1890, No. 15,424, and April 13, 1891, No. 6,283.

To all whom it may concern:

Be it known that, I JOHN BOULTBEE BROOKS, manufacturer, a subject of the Queen of Great Britain, residing at Great Charles Street, in 5 the city of Birmingham, England, have invented certain new and useful Improvements in Cycle-Saddles, (for which invention Letters Patent have been granted to me in Great Britain, bearing date September 30, 1890, No. 15,424, and April 13, 1891, No. 6,283;) and I do hereby declare the following to be a full, clear, and exact description of the invention, reference being had to the accompanying drawings, which form part of this specification.

15 This invention relates to detail improvements in the framings, springs, and accessory fittings of cycle-saddles.

Figure 1 of the accompanying drawings represents, partly in elevation and partly in 20 vertical section, a cycle-saddle provided with framings and fittings constructed and arranged according to my invention. Fig. 2 represents an under side plan of the base-framing and supporting-springs of the same. 25 Fig. 3 represents a transverse section with some of the parts in elevation and upon the dotted lines A B, Fig. 1, of the L-pin-boss connection, or the means of connection between the L-pin or saddle-iron and the base-framing.

30 a is the saddle-seat.
b are the seat-frame rods, arranged in double and nearly parallel order and located under the said seat and with the fore part of them 35 joined at b² to the connection or junction b³ of the top terminal members d² of loop-coiled springs d, whose lower terminal members d³ are attachably connected to the fore part f' of a trussed base framing or bracket f by a 40 screw-pin d⁴.

The back end of the seat of the saddle is supported upon pillar-coiled springs c, which are at their lower ends connected to a cross end f² of the said trussed base-framing by 45 pins or pegs f⁷, upon which the said ends of the springs may be vertically adjustable, while their upper ends are connected in common with the looped ends b⁴ of the rods b to the back under side a² of the saddle by screw 50 pins and nuts a³, depending from and affixedly connected to the said saddle-seat. The

base-framing f is composed of a top-pierced member f³ and angularly-directed lower members f⁴, united at their extreme ends by fore-and-aft parts or connections f⁵ f². Thus it 55 will be seen that the base-framing is trussed or constructed after the manner of a skeleton beam of the figure of a triangle. The middle part of the said base framing or bracket is fitted or provided with an L-pin boss i, jointed 60 by opposite or side pivots i² to the lower members f⁴ of it and having a horizontal hole i³ directed through it for the taking of the horizontal arm of the saddle-iron or L-pin, which is affixed in position by the screwing home of 65 the screw-pin i⁴. The upper part of the said boss has a neck i⁵, through the middle of which a screw-pin i⁶ takes for the affixing or clamping of the said boss at an angle relative to the framing; hence the imparting of tip or tilt to 70 the saddle. To accomplish the said tipping or tilting the middle part f⁵ of the top member f³ is curved or cambered to the radius of the pivots i². Likewise is the crown i⁷ of the boss, to the under side of the said cambered 75 part f⁵, which has a longitudinal slot or piercing f⁶, wherethrough the shank of the screw-pin i⁸ passes. Between the head of the pin i⁶ and the top part of the cambered part f⁵ is 80 a washer j.

The fore part of the framing is supported from a hanging bracket k, with a screwed hole k² through it, wherethrough the wormed part of a tensioned screw l passes and with its plain end l² taking into a plain hole b' of 85 the junction-piece b⁸. By rotating the said screw l the saddle-seat's tension is adjusted.

Having described my invention, what I claim as new is—

1. In a cycle-saddle, the combination, with 90 the seat-framing and springs, of a base-framing composed of trussed parts f³ f⁴, and with the latter f⁴ directed angularly to the former, substantially as described and set forth.
2. In the base-framing of a cycle-saddle, 95 the combination, with a trussed bracket, of a pivotally-mounted L-pin boss i i² i³ i⁴ i⁵ i⁶, as set forth.
3. In a cycle-saddle, jointing the fore part or parts of the frame-rods b to a junction-piece b⁸ or to the terminal upper members d² of loop-coiled springs d, as set forth. 100

4. In a cycle-saddle, the combination, with frame-rods b , connected at their rear ends to the under side after part of the seat of the saddle and at their fore ends to a junction-piece b^3 of the branches d^2 of a spring or springs d , as set forth.

5. In a cycle-saddle, the combination, with jointed frame-rods b b^2 b^3 , of loop and pillar coiled springs d c , the former disposed forward of the saddle-seat and the latter under the after end, as set forth.

6. In a cycle-saddle, the combination, with

the seating framing-rods b , of a joint b^2 , junction-piece b' b^3 , tension-screw l l^2 , and bracket k k^2 , as set forth.

In testimony that I claim the foregoing I have hereunto set my hand this 26th day of March, 1892.

JOHN BOULTBEE BROOKS.
